DESIGN FOR A TOASTER

Jean O. Reinecke and James F. Barnes, Chicago,
Ill., assignors to McGraw Electric Company,
Elgin, Ill., a corporation of Delaware

Application August 19, 1939, Serial No. 86,789

Term of patent 7 years

To all whom it may concern:

Be it known that we, Jean O. Reinecke and James F. Barnes, citizens of the United States, both residing at Chicago, in the county of Cook and State of Illinois, have invented a new, original, and ornamental Design for a Toaster, of which the following is a specification, reference being had to the accompanying drawing, forming part thereof, in which

Fig. 1 is a side elevational view of a toaster showing our new design, and

Fig. 2 is an end elevational view thereof.

The dominant feature of the design resides in the portions shown in full lines.

We claim:

The ornamental design for a toaster, substantially as shown and described.

JEAN O. REINECKE.
JAMES F. BARNES.
